UNITED STATES PATENT OFFICE.

THOMAS CRISP AND THOMAS FRANCIS MARION CRISP, OF JUNCTION, TEXAS,
ASSIGNORS OF ONE-THIRD TO JACK TURNER, OF JUNCTION, TEXAS.

WATER MOTOR.

1,415,996.

Specification of Letters Patent. Patented May 16, 1922.

Application filed September 13, 1920. Serial No. 409,894.

To all whom it may concern:

Be it known that we, THOMAS CRISP and THOMAS FRANCIS MARION CRISP, citizens of the United States, residing at Junction, in the county of Kimble and State of Texas, have invented certain new and useful Improvements in Water Motors, of which the following is a specification, reference being had to the accompanying drawings.

10 This invention relates to water motors.

An important object of the invention is to provide in a water motor a novel and efficient structure materially increasing the value thereof.

15 A further object of the invention is to provide means for preventing water motors of the spiral vane type being rendered less efficient by the action of the water tending to prevent rotation thereof. To this end 20 we provide a rotatably mounted shaft having attached thereto oppositely directed spiral compound vanes each compound vane consisting of a plurality of smaller vanes arranged transversely of the spiral line of 25 the vane proper.

Other objects and advantages of the invention will become apparent throughout the course of the following description.

In the accompanying drawings, wherein 30 for the purpose of illustration is shown a preferred embodiment of our invention, and wherein like reference characters designate like parts throughout:

Figure 1 is a plan view of a water motor 35 constructed in accordance with our invention, the casing being partly broken away.

Figure 2 is a detail view showing the mounting of the shaft, and

Figure 3 is an end elevation thereof.

40 Referring now more particularly to the drawings, the numeral 10 indicates a conduit connected with any suitable water pressure supply, provided at its ends with transverse members 11 and 12 in which is rotatably 45 mounted a shaft 13 extending longitudinally of the conduit 10 and coaxial therewith.

The shaft 13 is preferably provided with reduced ends 14 and 15. The member 11 at the forward end or entrance of the conduit has an opening 16 formed therein for the reception of the reduced end 14, and this opening has mounted therein the stationary portion 17 of a thrust bearing which is preferably provided with an outstanding 55 flange 18 secured to the member 11 at the

sides of the opening 16. The rotatable member of the thrust bearing is secured to the shaft upon the reduced extension 14 thereof and abuts the stationary member 17 through medium of the usual thrust balls. The forward end of the opening 16 is covered by a plate 20. The rear cross member 12 has a similar opening formed therein within which is mounted the stationary member 21 of a thrust bearing. The end 15 of the shaft 60 is threaded and has adjustably mounted thereon the rotatable member 22 of the thrust bearing which engages its stationary member with the interposition of thrust balls.

The shaft 13 has attached thereto diametrically oppositely extending compound vanes or series of compound vanes S each series being composed of a plurality of vanes V angularly disposed with relation to the shaft. Each vane V of a series is approximately scoop-shaped in general outline, the water being received upon the concave face. The surfaces α of adjacent vanes are parallel, and the compound vane as a whole is oblique to the axis or spirally arranged, and each 70 vane of a series is arranged oblique to the spiral of its series. Each of the vanes is slightly concavo-convex, thus forming in each series a plurality of buckets. Each of the spiral series is of sufficient length to form 75 one half turn or more upon the shaft.

In operation of our device the water passing through impinges successively upon each of the buckets of the series to cause rotation of the shaft and vanes. This rotation 80 is not opposed by the water passing through the conduit to any material extent, because of the fact that spaces are formed intermediate the vanes or buckets V. The slight back pressure caused by the action of the water upon these vanes assists in overcoming the longitudinal thrust of the shaft, which is greater than is ordinarily present in the straight spiral vane construction. In order 85 to overcome the overbalance of thrust the thrust bearings previously described have been provided. It will be noted that these thrust bearings have their stationary portions opposing shifting of the shaft in the direction of passage of the motive fluid and 90 it will furthermore be noted that these thrust bearings are adjustable, to compensate for wear.

It will be obvious that our device by reason of its simplicity of construction and 110

efficiency in operation is particularly well adapted for the use for which it was intended, and it will likewise be obvious that the construction herein is capable of some change without departing from the spirit of the invention. We do not, therefore, limit ourselves to the specific construction hereinbefore set forth, except as so limited by the subjoined claim.

10 Having described our invention, what we now claim is:

In a water motor, a rotatably mounted shaft, diametrically opposed spirally ar-

ranged series of scoop-shaped vanes secured to said shaft, each vane of a series being 15 spaced from the adjacent vanes of the same series and being disposed at an angle to the spiral path of the series, the surfaces of adjacent vanes being approximately parallel and the water being received upon the concave sides of the vanes, substantially as described.

In testimony whereof we hereunto affix our signatures.

THOMAS CRISP.

THOMAS FRANCIS MARION CRISP.
